UNITED STATES PATENT OFFICE.

MORRIS MALAWISTA AND WOLF SILBERMAN, OF BROOKLYN, NEW YORK.

COVER FOR LAUNDRY-TUBS.

1,180,059.

Specification of Letters Patent. Patented Apr. 18, 1916.

Application filed June 19, 1915. Serial No. 35,001.

To all whom it may concern:

Be it known that we, MORRIS MALAWISTA and WOLF SILBERMAN, citizens of the United States, residing at Brooklyn, county of 5 Kings, and State of New York, have invented new and useful Improvements in Covers for Laundry-Tubs, of which the following is a specification.

This invention relates to the method of 10 constructing metal laundry tub covers whereby the jointed plates are locked together and require no solder to make a perfect water tight closure.

The invention is essentially designed to 15 form a cover consisting of two galvanized metal plates, the object being to unite the plates so that the back of the cover will have no projecting parts or crevices for the lodgment of water or dirt. These tub covers 20 are usually made of galvanized sheet iron owing to its lightness and cheapness. Heretofore the upper and lower plates have been fastened with solder. This is very objectionable for the reason that the solder does 25 not hold well on the galvanized iron and soon comes off. When the solder comes off, the galvanized plates buckle or bend and the cover becomes useless. As will be hereinafter pointed out, my invention consists 30 in securing the plates by means of flanges so that it is entirely unnecessary to use any solder. In addition to dispensing with the solder, the construction of my fastening device is such that the lower plate at all times 35 holds the upper plate in a perfectly firm and rigid position and buckling is impossible.

The novel features of the invention are 40 more fully described in the following specification and claims and illustrated in the accompanying drawing in which:

Figure 1 represents a perspective top view of a cover embodying this invention. Fig. 2 is an inverted top perspective view of the 45 same. Fig. 3 is a horizontal section taken along the line $\alpha\alpha$ of Fig. 1 on a larger scale. Fig. 4 is a view of the top blank.

In this drawing the letter a designates a wooden frame which serves as a medium for 50 the core or foundation of the cover. On this frame is arranged a galvanized sheet metal plate b having a depression c located in the top of the plate. This plate is bent over the rim of the frame and it has a double portion d at its lower end. A plate e constit-

tutes the back of the cover. This plate has corresponding doubled end portions f for engagement with the portions d whereby the plate is united to the top. In this construction each plate has a fold and one laps 60 around the edge of the other to interlock the plates.

The frame a is provided with a channel g extending about the back of the frame so that when the lapped joints are pressed together they will sink into the channel so as to leave a flush joint h at the outer folds of the plates. It will be seen that by jamming the laps into the channel the back of the cover where it sets over the frame will be 70 entirely free of obstructions thereby obviating the lodgment of any foreign matter and facilitating cleaning of the cover.

As indicated in Fig. 2, the back plate is provided with a series of crimps i adapted 75 for engagement with the depressions in the back of the frame, for reinforcing the plate, and at the same time preventing movement of the plate.

The forward back portion of the cover is 80 provided with the usual elastic buffers j and the top of the cover has holes k for mounting the hinge butts whereby the cover can be mounted onto a laundry tub.

In Fig. 4 is shown a blank b of suitable 85 shape for forming the top of the cover. The inner dotted lines m in this figure denote the portions n of the flaps which are bent about the rim of the frame and the lines o of bending for the lapped joint. Two 90 of these flap members have wings p projecting from the mitered part q of the plate and adapted when the plate is fitted on to the frame to be bent over an edge of the rim and fastened by a clout nail as indicated in Fig. 2, thereby preventing shifting 95 of the plate relative to the frame.

We claim:

1. A cover of the kind described, comprising a frame, a top and back plate arranged on the frame, each having corresponding lapped interlocking portions parallel with the frame whereby the plates are united.

2. A cover adapted for use with laundry 105 tubs, comprising a frame, a top and back plate arranged on the frame, each having double portions lapped around the edge of each other located along the back parallel with the frame for uniting the plates.

110

3. A cover adapted for use with laundry tubs, comprising a frame, a top and back plate arranged on the frame, and means including corresponding lapped portions on each plate parallel along the back of said frame to lie flush with the back plate for interlocking the plates.
4. A cover adapted for use with laundry tubs, comprising a frame provided with a channel, a top and back plate arranged on the frame, each plate having double portions lapped around the edge of each other for uniting the plates, said uniting portions being sunk into the channel.
- 10 5. A cover adapted for use with laundry tubs, comprising a frame provided with a channel, a top and back plate arranged on the frame, each plate having double portions lapped around the edge of each other for uniting the plates, said uniting portions being sunk into the channel, and one of the
- 15 20

plates having wings for engagement with the rim of the frame.

6. A cover adapted for use with laundry tubs, comprising a frame provided with a channel, a top and back plate arranged on the frame, each plate having double portions lapped around the edge of each other for uniting the plates, said uniting portions being sunk into the channel, the front plate 30 having wings for engagement with the rim of the frame, and the back plate being provided with crimped portions for fastening the plate to the back of the frame.

In testimony whereof we have hereunto 35 set our hands in the presence of two subscribing witnesses.

MORRIS MALAWISTA.
WOLF SILBERMAN.
